UNITED STATES PATENT OFFICE.

CHARLES P. STANBON, OF SAUGUS, MASSACHUSETTS, ASSIGNOR TO UNITED SHOE MACHINERY COMPANY, OF PATERSON, NEW JERSEY, A CORPORATION OF NEW JERSEY.

MACHINE FOR FOLDING PLIABLE MATERIAL.

1,211,982.

Specification of Letters Patent.

Patented Jan. 9, 1917.

Application filed September 6, 1910. Serial No. 580,723.

To all whom it may concern:

Be it known that I, CHARLES P. STANBON, a citizen of the United States, and a resident of Saugus, in the county of Essex, 5 Commonwealth of Massachusetts, have invented an Improvement in Machines for Folding Pliable Material, of which the following description, in connection with the accompanying drawings, is a specification, 10 like letters on the drawings representing like parts.

My invention relates to machines for folding the edges of pliable material, such as leather, and is particularly adapted for 15 folding the edges of certain parts of boots and shoes such as toe caps, vamps, back stays, etc., where it is desired to give them a more finished appearance.

My invention is intended to provide means 20 for folding the edge of the material evenly and smoothly, as well where the outline of the work is irregular and comprises sharp curves, as where it is more regular or even straight, a result which, so far as I am 25 aware, is not accomplished by any other machine at the present time.

One embodiment of my invention selected for illustration and description herein, is shown in the accompanying drawings 30 wherein;

Figure 1 is a side elevation, various parts being, in places, broken away for clearness; Fig. 2 a front end elevation, a portion of the top being broken away; Fig. 3 a plan 35 of that portion of the work table immediately beneath the folding members on the line 3—3 of Fig. 2, showing the lower end of the hammer in section; Fig. 4 a vertical, sectional view from the right, on the line 4—4, Fig. 3, showing a portion of the forward part of the machine below the work table with the principal folding members in 40 elevation; Fig. 5 a vertical, sectional, longitudinal view on the line 5—5, Fig. 3, showing the cutter block and work table, the folder and some of its immediate connections in section; Fig. 6 a partial, vertical section on the line 6—6 of Fig. 1, looking from the front of the machine; Fig. 7 a 45 partial, vertical section on the line 7—7, Fig. 1, looking from the rear; Fig. 8 a perspective of the folding members showing the work in position to be folded thereby; and

Fig. 9 a longitudinal elevation of the cutter block and edge turner looking from the right, Fig. 1.

The folding operation, according to my invention, consists substantially of the following steps, first, feeding the work upon an edge turner which turns up the cemented 60 edge of the work, and, practically simultaneously therewith, when desired, slitting the same to insure eventual smoothness of the folded edge; second, folding the upturned and slitted edge by means of a folding finger, the edge being folded over a folding feed finger in the form of a hook which acts as a guide therefor and which determines the line of fold; and lastly, 65 hammering the folded edge to insure the retention thereof by the cement.

Referring first to Fig. 1, my invention is shown embodied in a machine comprising a hollow bed, having an overhanging arm 2, which serves as a support for various operating members and one side wall of which is largely broken away in this figure for clearness. The bed is adapted to rest or be secured upon a bench or be supported upon 75 suitable legs as desired. The bed is provided at its forward end, and immediately beneath the down-turned end of the arm 2, with a work table 3, herein shown as circular.

Extending longitudinally of the bed, and 80 suitably mounted in bearings therein, is a driving shaft 4, upon the rear end of which is secured a hand wheel 5, the hub 6 of which extends to the end of the shaft 4 and is secured thereon by a washer and screw 85 6^a. A loose stepped pulley 7, shown herein partly in section, and adapted to receive power from a suitable source, is mounted loosely on the hub 6 of said hand wheel 5. The face of the wheel 5, adjacent to the loose pulley 7, is grooved to receive a friction member 5^a, as of leather, to make frictional contact with the stepped pulley 7 when the latter is pressed against it. A usual ball bearing 8 is provided between the hub 6 of the hand wheel 5 and the arm 2, and a spring 9, encircling the hub of the wheel and interposed between said wheel 5 and the hub of the stepped pulley 7, serves to keep said wheel and pulley normally out 100 of engagement. Similarly mounted in said

head, and nearer one side thereof, see Figs. 1 and 2, where it is partly broken away, is a clutch shaft 10. This shaft, see Fig. 1, has secured to its rear end an upwardly and 5 rearwardly extended clutch arm 11 provided at its end with a downwardly extended pulley engaging finger 12, the inner face 13 of which is beveled longitudinally thereof, and stands opposite the outer end of the stepped 10 pulley hub. The clutch arm 11 and its finger 12 are secured to the clutch shaft 10 in such position that when the stepped pulley 7 is out of engagement with the hand wheel 5, the lower end of the inner face 13 of said 15 finger 12 just engages the rounded tip 14 of the hub of said pulley. The shaft 10 is provided, within the bed, see Figs. 1 and 7, with a laterally extended treadle arm 16 adapted to be connected at its end to a foot 20 treadle, not shown. By means of this treadle the shaft 10 may be rocked to throw the finger 12 downwardly and cause the beveled inner face 13 thereof to impinge on the end 14 of the stepped pulley 7, to force 25 it into frictional engagement with the hand wheel 5 to rotate the latter. At the opposite or front end of said shaft 10, see Fig. 1, a coiled spring 17, interposed between a washer 18 on the end of said shaft and the 30 bed, serves to retain the finger 12 always in effective engagement with the hub of said pulley 7, to hold the latter on the shaft 4, and also to permit longitudinal movement of the shaft 10 during adjustment of the 35 feeding mechanism to be described. The treadle arm 16 and shaft 10, Fig. 7, are returned to normal position by a spring 16^a encircling said shaft, one end of said spring bearing against the wall of the bed, while 40 the opposite end bears against the lower face of the treadle arm 16.

On the rear end of the clutch shaft 10, Fig. 1, between the clutch arm 11 and the bed, a brake member 19, provided with a 45 suitable shoe, not shown, may be secured, by set screws, in such position thereon, that when the finger 11 is raised by the rocking of the shaft to free the stepped pulley 7 from engagement with the hand wheel 5, 50 said brake 19 will engage the latter wheel and immediately stop rotation thereof.

The feed mechanism, Figs. 1, 2 and 4, consists herein of a feed wheel 20 with its hub 21, secured to the forward end of a hollow feed shaft 22, Figs. 1, 4, mounted in bearings in the bed. The periphery of this feed wheel is provided herein at its forward edge with a lip 22^a, the inner wall of which is beveled, said lip extending slightly above 60 the top of the work table. This feed wheel is given intermittent motion in one direction by means presently to be described. The other and co-operating feed member consists, as here shown, of a slender upwardly inclined combined folding and feed finger in 65

the form of a hook 23, the upper end of which is bent downward and under to form a hook 24 positioned to co-operate with the feed wheel 20 by engaging the work on the opposite side therefrom, and pressing the 70 same thereagainst, and which serves both to assist in feeding the work in a manner to be described, and also as a gage and rest against and over which the work is folded by the folding finger. 75

Referring to the feed hook 24, Figs. 1, 2 and 4, the shank 23 thereof is secured, as by a screw 25, in the split end 26 of a cylindrical feed hook carrier 27, slidably mounted in a yoke 28 angularly depending from a hub 29 secured to the forward end of a second feed shaft 30 within the hollow feed shaft 22 referred to. The shank 23 of the feed hook may be provided with a key or any other suitable means for preventing rotation thereof in the end of the carrier. The upper end of the yoke 28 is split and the two parts thereof are secured about the carrier 27 as by a screw 31. A spring 32 coiled about the lower end of the carrier 27 and interposed 85 between a nut 33 thereon and the lower end of said yoke, acts normally to retain said feed hook carrier in its lower or feeding position as shown in Fig. 4. 90

The above described feed hook 23 and feed 95 wheel 20 are actuated, Fig. 7, by means of a cam 34 on the driving shaft 4, through the medium of a novel lever and link connection with the shaft 30 and by means of said lever and link connection with a clutch device secured to the hollow shaft 22. The said cam 34 acts upon a roll 35, see Fig. 7, on the inner end of a longitudinally slidable stud 36 mounted in a bracket 37 depending within the bed and kept in engagement with said 100 cam by a spring 38 encircling the extended end of said stud and interposed between a lever 41 thereon and an adjustable stop 40 shown herein as a sleeve with a hexagonal outer end threaded into the bed, and through 105 which the stud extension 36 is free to slide. Between the two ends of the stud 36 is pivotally connected the lower end of the lever 41 fulcrumed intermediate its ends and connected by a link 42, with the end of an arm 43 fast on the end of the inner feed shaft 30 operating the feed hook. 110

The lever 41, see Fig. 7, has a sliding fit in a transversely extended fulcrum pin 45, mounted at its ends in opposite faces of a cylindrical fulcrum block 46 slidably mounted in an upright boss 47 in the bed. Said block 46 has herein two depending arms 48 which are connected at their lower ends to an arm 49 loose upon a shaft 50 suitably mounted in the bed. Oscillation of the arm 49 thereby raising and lowering the fulcrum block 46 will vary the length of feed of the feed hook as desired. The arm 43, Fig. 7 is forked at 44 and receives the pin 115 120 125 130

53 of a friction clutch 51, arranged to impart step by step rotation to the outer feed shaft 22.

It is evident from the foregoing that rotation of the shaft 4 and cam 34 thereon will impart oscillatory motion through the roll 34 and stud 36 to the lever 41, the pin 45 acting as a fulcrum therefor, and by means of the link 42 and arm 43 impart oscillatory movement to the shaft 30 and feed hook 23 thereon and by means of the pin 53 on said clutch 51 transmit intermittent motion in one direction, herewith the right, Fig. 7, to the shaft 22 and feed wheel 20 thereon, and that said motion will be simultaneous with the forward motion of said hook. It is obvious that by raising or lowering the block 46 and thereby the pin 45 the fulcrum of the lever 41 will be so moved that the throw of the upper end of said lever will be correspondingly increased or diminished and consequently also the extent of the feeding movement of said hook 23 and wheel 20 actuated and controlled by the movement of said lever. A spring 53^a secured to said arm 49 and to the arm 2, serves to return said arm 49, block 46 and its fulcrum pin to their upper and normal positions which, as shown herein are adapted to provide the minimum feeding movement.

For the purpose of raising and lowering the block 46 and varying the extent of feed of the feeding members at will, I have shown one end of the front bar of the arm 16 on the shaft 10, referred to, provided with a roll 54 which, in its normal position, is directly over the arm 49 and a short distance above it. Depression of the arm 16 as by a treadle, not shown, will therefore, if of sufficient extent, not only rock the shaft 10 to throw the loose pulley 7 into engagement with the wheel 5 as described, but will cause the roll 54 to impinge on the upper face of the arm 49 and depress the latter, thereby drawing downward the fulcrum block 46 and fulcrum pin 45, and increasing the throw of said lever and the extent of the feeding movement thereof. Such depression of the lever 16 and rocking of the shaft 10 will not affect the operation of the clutch finger 12 in holding the pulley 7 in engagement with the hand wheel 5 since, after said wheel and pulley clutch are in engagement, further rocking of the shaft 10 and depression of the finger 12 are permitted by the spring 17 at the forward end of said shaft which permits the shaft to move longitudinally in its bearings without disconnecting the hand wheel 5 and stepped pulley 7.

To enable the feed hook 23 to be raised and freed from the work after each feeding movement and returned for a new engagement with the work, I have provided (Figs. 2 and 4) a cam wheel 55 at the forward end of the main shaft 4, in engagement with a

roll 56 on the end of a stud 57, at the under face of the feed hook carrier 27, whereby the carrier and its feed hook 23 are angularly raised in the yoke 28 and from the work, at the proper times, and returned by means of the spring 32 heretofore referred to.

Before describing the action of the folding finger proper, I will explain the means provided for presenting the edge of the material in an advantageous position for the folding thereof. This means, Figs. 2, 3, 8 and 9, comprises a combined cutter block and edge turner 58 preferably of some soft material, as brass, set substantially flush into the upper face of the removable central section 59 of the work table and secured thereto, herein by screws 60. The outer side 61 of this cutter block, being the lower edge Fig. 3, gradually rises and curves inwardly toward the inner end of the block adjacent the hook 24 and, at its end, just beneath said hook, meets the opposite side of the block, thus providing an upwardly and inwardly inclined surface 63 which acts upon the edge of the material fed against it and turns said edge upwardly preparatory to folding and also to present it to the cutter to be described. At a point substantially, herein, halfway up said incline, a vertical gage or guide pin 64 is fixed against which the edge of the material is guided so that an even fold is obtained. As the edge of the material is fed up said inclined surface 63, Figs. 3 and 9, said edge is gradually raised until, at the inner end of said incline, it is in a substantially vertical position, ready to be folded down over the hook 23 by the folding finger to be described while the body of the material is beneath said hook. To retain the edge closely against the surface 63 of the combined cutter block and edge turner 58, and to prevent said edge from curling over before it reaches the folder, which would cause infolding, I provide the edge of the cutter block with a work holding finger, comprising a shank 65, held in a groove in the upper face of the removable section 59 by a screw 67, said shank, at its inner end adjacent the hook being turned angularly upward at 68 and then inward and downward at 69 so as to conform generally to, but separated slightly from, the surface of the cutter block, the tip of said finger being turned slightly outward away from said block to facilitate passage of the work beneath it. This finger acts as a sort of presser to hold the upturned edge of the material flat against and upon the upwardly inclined face of said cutter block, thereby to prevent it from curling away and infolding, as described.

The folding member proper, see Fig. 4, comprises a curved folding finger 70 substantially vertically positioned and secured at one end, see Fig. 5, to a short, horizontal

rock shaft 71 having bearing in opposed grooves in the upper and lower faces respectively of the removable central section 59 of the work table 3, and a cover plate 72 therefor. Said shaft 71 intermediate its ends, Fig. 5, has a depending forked arm 73 to which is pivotally connected one end of an actuating lever 74 fulcrumed at its opposite end to the forked head of a screw 10 stud 75 threaded into and thereby adjustably secured to the front of the bed. At a point opposite the end of the main shaft 4, said folder actuating lever 74 is provided with a roll stud 76, Figs. 1, 2 and 4, which 15 engages a cam face 78 on the inner surface of the hook actuating cam wheel 55 already described. A guide for the lever 74 in the form of a vertically slotted stud 79, Fig. 2, is threaded into the front wall of the bed, 20 and said stud is drilled centrally and longitudinally to receive a coiled spring 80 which presses outward on and acts to retain the roll 76 against the cam surface 78. Thus rotation of the shaft 4 and cam 78 25 causes the lever 74 to be rocked on its fulcrum 75, and impart a forward and downward folding movement to the folding finger 70 and causing the same to fold the raised edge of the material down over and upon 30 the inturned end of the hooked folding feed finger 24.

In order to fold the edge of the material smoothly and evenly where said edge is sharply curved, it is desirable to slit said edge at frequent intervals, and for this purpose I have provided a slitting knife 81, Figs. 1 and 2, which is removably secured to and in the forked ends of an upwardly and rearwardly inclined knife carrier 82 by 40 a screw 83, a V-shaped slot 84 in the upper end of the knife, see dotted line Fig. 1, being engaged by a similarly shaped projection 85 in the knife carrier holding the knife firmly in position. This knife slides 45 in suitable bearings in the arm head and to operate it I provide an eccentric 86 on the main shaft 4, which eccentric is pivotally connected by a right and left threaded link 87 with a screw 88 threaded into and movable in the short arm 90 of a bell crank lever, fulcrumed at 92 in the arm 2. The opposite front end of said lever is connected by a link 93 with the upper end of 50 said knife carrier 82. Rotation of said main shaft 4 imparts reciprocatory motion to said knife 81.

The knife in its reciprocations cuts upon the cutting block referred to, and upon the material fed over said cutting block as 60 described. Repeated sharpenings of said knife after it has become dull from use, shorten the length thereof, and to offset this shortening of the blade, and also to accommodate any slight difference in the 65 length of the blades when new, I have pro-

vided means for adjusting the position of the knife carrier. This means, see Fig. 6, comprises herein a link 97 connected at one end to the joint between the eccentric arm 98 and right and left threaded link 87, and at its opposite end connected to the upper arm of a bell crank lever 100 fast to the shaft 50 referred to. The lower arm of said lever 100 has a recess at one face thereof to receive one end of a coiled spring 103, the other end of which is seated against an adjusting screw in the inner wall of the bed. The opposite face of said lever arm is engaged by the end of an adjusting rod 104 fitted at its other end with a hand wheel 106, having threaded engagement with a split bearing block 107 adjustably secured to said bed. A clamp screw 108 furnishes means by which said split head bearing block may be tightened about the rod 104 to create sufficient friction to remove all danger of said rod and the knife getting out of adjustment. By the described means it is clear that the joint 99 between the eccentric rod 98 and link 87 may be shifted 70 like a toggle joint to lower or raise the knife relative to the cutting block 58. For raising the knife from the work entirely, as, for instance, when approaching a seam, I have secured, see dotted lines Fig. 6, an 75 arm 105 to the shaft 50, and by means of a treadle, not shown, this arm may be depressed at any time by the foot to throw the upper arm 100 of the lever forward collapsing the toggle joint and withdrawing 80 the knife from the work.

The eccentric 86 is so adjusted on the shaft as to time of rotation that the knife is caused to slit the partly upturned edge of the work just before it is engaged by 105 the feed hook 24, said knife cutting against the beveled face 63 of the cutter block at a point where it is substantially at an angle of 45°. By this angular arrangement of the knife and cutting block the edge of 110 the work is slit while in a natural position without stretching the same. If the knife operated vertically against a flat cutting block part of the edge of the work would be pressed down thereby upon said cutting block, and the distance between the portion of the edge folded down upon the hook 24 and the unfolded portion engaged and compressed by the knife is so short that such compression by the knife would stretch 115 said edge and cause a fullness and unevenness in the folded edge. Close to the folding finger 70 and in a position to engage the folded edge as soon as the finger has acted upon it is a hammer 110, which drops with a slight inward movement thereof upon and hammers the parts of the folded edge of the work tightly together and also holds the edge down upon the work table 120 while the folding finger 70 and feed hook 130

24 are raised preparatory to the next engagement with the work. This hammer is shown herein as comprising a substantially rectangular shank 110 provided at its lower end 5 with a flaring head 111, the flaring edge adjacent the folding finger being curved somewhat to extend toward and somewhat ~~about~~ 10 the end of said finger and hook to prevent, so far as possible, the folded edge 15 from being raised by the feed finger on its upward movement preparatory to further engagement with and feeding of the work. The hammer 110 is drilled longitudinally and herein centrally, to receive 20 a presser pin 111^a, extending slightly below the end of the hammer head 111 and retained therein by a locking pin 111^b extending laterally from said presser pin into slots in opposite faces of the hammer shank 110 25 and permitting longitudinal movement of the pin 111^a relative to said hammer. A spring 111^c is interposed between the upper end of the presser pin 111^a and the top of the passage in which said pin moves, 30 which spring normally yieldingly presses said pin 111^a downward as far as the pin 111^b and said slots permit. This pin 111^a engages the work on the downward movement of the hammer 110 in advance of said 35 hammer and also remains in engagement with the work after said hammer has begun its upward travel. This prolonged engagement of the presser pin 111^a with the work serves two purposes; first, it avoids the danger 40 of the work being raised from the table, on the upward travel of the hammer, by suction, or the cement on the work adhering to the head of the hammer; and it also serves to retain the work in position on the 45 table after the hammer has begun its upward travel and until the feed finger 24 has securely engaged said work to feed the same. In this way all danger is removed of the work being displaced from its proper position on the table between successive folding and feeding steps.

The hammer moves in a groove 112 in a block 113 pivotally secured to the end of the arm 2. The upper end of the hammer shank 110 terminates in a round rod 114 having a spring 115 coiled thereabout, one end of which bears against a nut 116 threaded on said rod somewhat above the rectangular shank, while the opposite end of 55 said spring rests against the end of a sleeve 117 on the upper end of said rod, secured thereon by a nut 118 which provides a bearing for the rod. Said sleeve is received by the forked end 119 of a lever 120 and is 60 pivotally secured thereto by the opposed pivot studs 121 threaded into the arms of said forked end, and engaging said sleeve at opposite points on the sides thereof. The described construction permits adjustment 65 of the hammer relative to the lever when

necessary and the spring permits the hammer to yield somewhat relative to the lever in emergencies, as for instance when a seam is encountered or the thickness of the goods is increased for any reason.

The lever is provided with a downwardly extended arm 122, the end of which is fulcrumed upon the eccentric hub 123 of a crank 124 pivoted upon the walls of the machine arm by a screw bolt 125. The aforesaid crank 124 has a handle 126 provided with a spring pressed locking pin 127, which, entering a depression on the machine arm, serves to keep the said crank in desired position. By withdrawing the pin from 80 said depression the crank may be turned to raise said lever, withdraw the hammer from the work and permit the work to be withdrawn from the machine.

To cause the hammer to descend and engage the work regularly and hold the same securely while the feed hook 24 is raised and returned for further engagement with the work, the inner end of the lever 120 is pivotally connected to the upper end of a link 129 by a stud 130, the inner flattened end of which is pivoted to the forked upper end of said link, the stud itself being rotatively held in the squared end of the lever 120 which is bored to receive the same with 95 a sliding fit. The inner end of the stud 130 is provided with a roll 133 adapted to travel in a groove 134 in the wall of the arm and thereby guide the movements of said lever on the upper side of said link. The lower 100 end of the link 129 has threaded engagement with the strap of an eccentric 136 on the main shaft 4.

Having described the functions and particular operation of the different members 105 of the embodiment of my invention illustrated herein, performing the separate steps of the folding operation, I will briefly describe the action of the machine as a whole. The operator facing the side of the machine 110 shown in Fig. 1, rotates the hand wheel 5 until the feed hook 24 and folding finger 70 are in their uppermost positions, when the hammer 110 will be in its lowermost position, and the knife 81 intermediate its uppermost and lowermost positions and just above the inturned point of the feeding hook 24. The operator then places the work on the table 3, with that point of the edge of the work first to be folded directly beneath the tip of the hook 24, said edge abutting the gage pin 64, underlying the presser finger 69 and overlying the diagonally upwardly inclined upper face 63 of the cutter block and edge turner 58 as shown in Fig. 8. 115 Rotation of the shaft 4 through the eccentric 86 thereon, the link 87, lever 90, and link 93 imparts further upward movement to the knife 81; rotation of the cam 55 on said shaft allows the spring 32 to depress 120 125 130

the carrier 27 and its feed hook 24, and the eccentric 136, by means of the link 129 and lever 120 raises the hammer 110, the presser pin 111^a remaining in engagement with the 5 work a short period of time after the hammer begins its upward travel to hold the work until the feed finger engages it securely.

When the hook 24 reaches the limit of its 10 downward travel and engages the work, the rocking of the shaft 30 by means of the cam 34, stud 36, lever 41 and link 42 connected to the arm 43 on said shaft and the intermittent motion imparted to the hollow shaft 15 22 by the aforesaid means in connection with the pin 53 and clutch 51 on the shaft 22 cause the hook 24 and feed wheel 20 with the work between them to feed the same away from the operator. The work is fed 20 up the inclined face of the cutter block and edge turner 58 beneath the presser finger 69 and in front of the folding finger 70, the knife 81 continuing its travel upward. Just before the hook 24 and wheel 20 reach 25 the limit of their feeding movement the knife begins its downward movement to slit the edge of the work, if said edge is curved, to facilitate the smooth folding thereof.

As the hook 24 and wheel 20 position the 30 work before the folder 70 and cease to feed, the movement of the roll 76 upon the face of the cam 78 causes the lever 74 to throw the folder 70 forward against the substantially upright edge of the work, thereby 35 folding the same down and upon the in-turned end of the folding hook 24, which acts as a gage to assist in determining the line of fold and also as a rest therefor. As the feeding movement of the hook 24 and wheel 20 40 ceases the hammer begins to descend. The hook remains stationary while the folder is folding the edge of the work as described, the hammer and knife continuing their downward travel. The hammer descends on 45 the folded edge of the work, as the same is fed to it after the first folding movement of the folder, and hammers it together to insure the adhesion thereof by means of the cement previously applied thereto, the inward movement of the hammer head wiping the in-turned edge of the work over upon the work as far as the crease made by the folder will permit, insuring a straight edge therefor.

50 The knife contacts with the work at an angle of substantially forty-five degrees on the inclined face of the block 58 and cuts said work just before it is presented to the folder. This cutting of the work while the 55 same is in a raised angular position is an important advantage of this machine.

Some kinds of material, especially thin leather, stretch very easily and if the edge thereof is pressed down upon a flat surface 60 65 by a knife during the cutting operation,

while the adjoining portion of the edge is folded and held firmly by a folder or similar member said edge will stretch and pucker and prevent the even and smooth folding of the same. By my method of slitting the 70 edge this trouble is avoided.

The hook, knife and folder rise substantially together after the folding and slitting of the work, the hammer, however, continuing its downward movement where it engages the work as the hook leaves it the presser pin 111^a engaging the work slightly in advance of the hammer. The hook, by the continued rocking of the shaft 30 and forward motion of the shaft 22 and rotation of the cam 55 is then raised again and as it rises is moved toward the operator in position to again descend to engage and feed the work for a repetition of the steps as described. As the hook descends and engages the work it presses the same tightly against the lip on the feed wheel which thereby assists in forming an even folded edge by providing a sharp uniform edge over which the work is folded by the folding finger. It will be noticed that the presser finger keeps the edge pressed down smooth upon the block until it is fed before the folder, thereby preventing infolding of said edge.

95 The feeding members are preferably adjusted to give the work the minimum feed for the nature of the work in hand. Therefore, inasmuch as the movements of the knife and folder correspond in frequency to the actuation of the feeding members it will be evident since said feed is adjustable, that, by adjusting said members to provide a very limited feed at each actuation thereof, the knife and folding finger will operate upon closely adjacent portions of the edge 100 of the work which is thereby evenly and smoothly folded around the sharpest curves. The fact that the folding member is narrow and the rest upon which the work is folded is narrow also contributes to the possibility 105 of folding the edge smoothly around sharp curves.

If the edge of the work is straight or nearly so, it will be unnecessary to slit the same to fold it smoothly and evenly and in such a case, or if when folding about a sharp curve a seam in the goods is encountered, the knife may be raised to free it from contact with the work entirely. This may be done by depressing the arm 105 on the shaft 50 thereby rocking the same to cause the lever 100 to close, more or less the toggle joint 99, thus shortening the effective length of the link 87 and raising the knife 81. The hammer may be raised to permit withdrawal of the work or for any other reason by withdrawing the pin 127 from its seat and then depressing the crank 124, thereby raising the fulcrum of the lever 120 and also raising the hammer itself.

It would, doubtless, be possible to vary the described construction in details without departing from the spirit and scope of my invention, and

5 Having shown one embodiment thereof I claim:

1. In a machine for folding pliable material, the combination with folding instrumentalities, of a hammer, and means for 10 moving said hammer downwardly and inwardly upon the margin.

2. In a machine for folding pliable material, the combination with folding instrumentalities of means to determine the line 15 of fold and an inthrowing hammer arranged to operate upon the folded edge.

3. A machine of the class described having, in combination, a frame, folding instrumentalities, a vibrating slitting knife, 20 an actuating shaft, driving connections between the shaft and knife for vibrating the knife normally in a path which intersects the work, said connections being constructed and arranged to be manipulated to move the 25 knife to inoperative position, and treadle operated means carried by the frame for accomplishing said manipulation at will during the operation of the machine.

4. A machine of the class described having, in combination, a frame, folding instrumentalities, a vibrating slitting knife, an 30 actuating shaft, driving connections between the shaft and knife for vibrating the knife normally in a path which intersects the work, said connections being constructed and arranged to be varied in effective 35 length for the purpose of moving the knife out of range of the work, and treadle operated means mounted on the frame for controlling the driving connections.

5. In a machine for folding pliable material, the combination with work feeding means of a slitting knife, means positively connected at all times with the knife for 45 vibrating it, a spring normally acting to cause the path of the knife to intersect the material, and means under control of the operator during the operation of the machine for changing the location of the path 50 of the slitting knife by acting in opposition to said spring to render said knife inoperative without interrupting its vibration.

6. In a machine for folding pliable material, the combination of means to feed the 55 work, means to slit the edge of the work, means to determine the line of fold, folding means, a presser, and means for moving said presser downwardly and inwardly to wipe over and press down the folded margin.

60 7. In a machine for folding pliable material, the combination of a bed, a work table, an inclined edge-turning cutter block, an edge-slitting knife, an edge-folding finger, feeding means comprising a feed wheel and 65 a feed finger, and a hammer to hammer

downwardly and inwardly the folded work edge.

8. In a machine for folding pliable material, the combination with folding instrumentalities, of a member having an edge to 70 determine the line of fold, and means for holding said member stationary during the folding operation.

9. In a machine for folding pliable material, the combination of a bed, a work table, 75 an inclined edge-turning cutter block, an inclined edge-slitting knife, an edge-folding finger, feeding means comprising a feed wheel and a hook-shaped feed finger, and a hammer having a lateral throw to hammer 80 downwardly and laterally the folded work edge.

10. In a machine for folding pliable material, the combination of a bed, a work table, 85 an inclined edge-turning cutter block, an edge-slitting knife for slitting the work edge when in an inclined position, a folding finger, feeding means comprising a flanged feed wheel and a hook-shaped feed finger, and an inthrowing hammer to hammer 90 downwardly and inwardly the folded work edge.

11. In a machine for folding pliable material, the combination of a bed, a work table, 95 an inclined edge-turning cutter block, an edge guide on the inclined face of said block, an edge-slitting knife for slitting the work edge when in an inclined position, a folding finger, feeding means comprising a feed wheel and a feed finger, and an inthrowing hammer to hammer downwardly 100 and inwardly the folded work edge.

12. In a machine for folding pliable material, the combination of a bed, a work table, 105 an inclined edge-turning cutter block, an edge guide on the inclined face of said block, an edge presser finger also for said block, an edge-slitting knife for slitting the work edge when in an inclined position, a folding finger, feeding means comprising a 110 feed wheel and a feed finger, and an inthrowing hammer to hammer downwardly and inwardly the folded work edge.

13. In a machine for folding pliable material, the combination of a bed, a work table, 115 an inclined edge-turning cutter block, an edge guide on the inclined face of said block, an edge presser finger conforming substantially to the face of said block, an edge-slitting knife arranged to move toward and from the cutter block for slitting the work edge when in an inclined position, a folding finger, feeding means comprising a feed wheel and a feed finger, and a hammer to hammer 120 the folded work edge.

14. In a machine for folding pliable material, the combination of a bed, a work table, an inclined edge-turning cutter block to turn the edge of the work to substantially 125 an upright position, an inclined edge-slit- 130

ting knife, a folding finger to engage the work in its raised position and fold the same and feeding means comprising a feed wheel and a feed finger.

- 5 15. In a machine for folding pliable material, the combination of a bed, a work table, an inclined edge-turning cutter block to turn the edge of the work to substantially an upright position, an edge presser finger 70
 10 to retain the work upon the inclined block until raised thereby and presented to the folding finger, a folding finger to fold the work edge and feeding means comprising a feed wheel and a feed finger.
 15 16. In a machine for folding pliable material, the combination of a bed, a work table, an edge-turning cutter block, an edge-slitting knife, a folding finger, and feeding means comprising a feed wheel and a combined feed finger, gage, and rest for the folded edge.
 20 17. In a machine for folding pliable material, the combination of a bed, a work table, an edge-turning cutter block, an edge-slitting knife, a folding finger, and feeding means comprising a feed wheel and a feed finger overlying the work, underlying the folded work edge and over which the edge is folded by said folding finger.
 25 18. In a machine for folding pliable material, the combination of a bed, a work table, an edge-turning cutter block, a knife, a folding finger, a hook-shaped member to determine the line of fold and variable feeding means whereby the feed may be varied during the folding operation to fold the edge smoothly around curves.
 30 19. In a machine for folding pliable material, the combination of a bed, a work table, an angular edge-turning cutter block, an angularly operative edge-slitting knife, a presser finger, a folding finger, variable feeding means comprising a lipped feed-wheel and a feed finger adapted to press the work against said lip to define the line for folding, said feeding means enabling the feed to be varied during the folding operation to fold the edge smoothly around curves and a hammer to hammer and wipe the folded edge to cause the same to remain in its folded position.
 35 20. In a machine for folding pliable material, the combination of an angularly faced cutter block, an angularly operative edge-slitting knife to slit the work thereon, means to withdraw the knife from the work, a folding finger to fold said slitted edge, a hook-shaped member to determine the line of fold and a hammer to hammer said folded edge firmly in position.
 40 21. In a machine for folding pliable material, the combination of an angularly faced edge-turning cutter block, an angularly operative edge-slitting knife to slit the work edge in a raised position thereon,
 45
 50
 55
 60
 65

means to vary the throw of and withdraw said knife from the work, a hook-shaped member to determine the line of fold and a folding finger to fold said slitted edge.

22. In a machine for folding pliable material, the combination of a feed wheel having intermittent feeding movement, a feed finger supported below and at one side of the work and overhanging the same, having a coöperating feeding movement with 75
 75 said wheel and an angular upward and substantially straight downward movement preparatory to said feeding movement, a folding finger adapted to fold the work over said feeding finger and a hammer for 80
 80 operating upon the folded portion of the material.

23. In a machine for folding pliable material, the combination of a cutter block, an edge-slitting knife, a folding finger, feeding means comprising a feed wheel and a feed finger, means to actuate the same, and means to vary the feed of said members comprising a rock-shaft, a lever therefor and means to vary the position of the fulcrum of said lever.
 85

24. In a machine for folding pliable material, the combination of a work table, a folding finger, a knife, feeding means comprising a feed wheel and a feed finger mounted in a carrier, a yoke guide therefor, means to impart rocking motion thereto and to said carrier and means to impart reciprocatory longitudinal movement to said carrier.
 90

25. In a machine for folding pliable material, the combination of an inclined edge-turning cutter block, feeding means comprising a feed wheel and a feed finger the end of which overhangs and is inturned to coöperate with said wheel to feed the work to said block and a folding finger positioned within said overhanging and inturned end to fold the work over upon said inturned end.
 95

26. In a machine for folding pliable material, the combination of feeding means comprising a feed wheel, a feed finger the end of which overhangs and is inturned to coöperate with said wheel, a folding finger positioned within said overhanging and inturned end to fold the work over and upon the same, said finger comprising a substantially upright member, means to operate the same comprising a rock-shaft carrying at one end thereof said finger and intermediate its ends a link pivotally connected to a lever, a support for said lever and means to actuate said lever to impart folding movement to said finger.
 100

27. In a machine for folding pliable material, the combination of a beveled edge-turning cutter block, a gage thereon, a presser finger therefor, a combined feed finger, gage and edge rest, a folding finger
 105
 110
 115
 120
 125

- to fold the turned edge of the work over and upon said edge rest as said edge leaves said block and an inthrowing hammer to compress and wipe inwardly said folded edge as it is folded. 5
28. A machine of the class described having, in combination, means for feeding a piece of material intermittently into position to have its edge operated upon, an edge rest and a folding finger past which the material progresses, means for causing relative movement between said rest and finger to form the fold, and means for pressing the fold. 10
29. In a machine for folding pliable material, the combination of a bed, a work table, a folding finger, a feed member, and a second finger overlying the work, underlying the folded edge and over which the edge is folded by said folding finger. 15
30. In a machine for folding pliable material, the combination of a bed, a work table, a folding finger, a feed member, a second finger overlying the work, underlying the folded edge and over which the edge is folded by said folding finger, and treadle actuated means for varying the movement of the feed member during the operation of the machine. 20
31. In a machine for folding pliable material, the combination of a bed, a work table, means for feeding the work intermittently across said table, a folding finger, and a treadle actuated means for varying the feed during the operation of the machine. 25
32. In a machine for folding pliable material, the combination of a bed, a work table, a folding finger, and feeding means comprising a combined feeding finger, gage and rest for the folded edge. 30
33. In a machine for folding pliable material, the combination of an edge turning member, a combined gage and edge rest, a folding finger to fold the turned edge of the work over said rest as said edge leaves said turning member, and a hammer to press the folded edge. 35
34. In a machine for folding pliable material, the combination of an angularly faced edge turning cutter block and an angularly operative edge slitting knife to slit the work edge in a raised position thereon, means to vary the throw of and withdraw said knife from the work, a folding finger to fold said slitted edge, and means for compressing the fold. 40
35. A machine of the class described having, in combination, folding and feeding mechanism comprising a folder held from movement in the line of feed, a combined feeding finger and creaser, and means for actuating said folder and combined member. 45
36. In a machine for folding pliable material the combination of a work table, a folding finger, a feed member, a second member overlying the work, underlying the folded edge and over which the edge is folded by said folding finger, and treadle actuated means for varying the movement of the feed member during the operation of the machine. 50
37. A machine of the class described having, in combination, means for feeding a piece of material intermittently into position to have its margin operated upon, means for progressively folding the margin, said last-named means including a folder and a creaser across the edge of which the folder moves, and means for varying at will, during the operation of the machine, the extent of the intermittent feed movements. 55
38. A machine of the class described having, in combination, means for feeding a piece of material intermittently into position to have its margin operated upon, means for progressively slitting and folding the margin, said last-named means including a creaser about the edge of which the fold is bent, and treadle actuated means for varying the extent of the intermittent feed movements during the operation of the machine. 60
39. A step-by-step folding machine having, in combination, a cutter for slitting the margin of a piece of material, a folder located to one side of the cutter in the line of feed, a presser located on the other side of the folder from the cutter, a creaser about which the slit margin is bent by the folder, means for actuating said cutter, folder and presser, means for feeding material intermittently thereto, and means capable of being operated at will during the operation of the machine for varying the extent of the intermittent feed movements. 65
40. A machine of the class described having, in combination, means for feeding a piece of material intermittently into position to have its margin operated upon, a creaser and a folder past which the material progresses, means for causing relative movement between the folder and creaser to form a fold, and means capable of being operated at will during the operation of the machine for varying the extent of the intermittent feed movements. 70
41. A machine of the class described having, in combination, means for feeding a piece of material intermittently into position to have its margin operated upon, means for progressively slitting and folding the margin, and treadle actuated means for varying the extent of the intermittent feed movements during the operation of the machine, said means comprising a movable feed controlling member, and yielding means tending normally to move said member to one limit of its path. 75
42. In a folding machine of the class described, a work feeding device, coöoperating folding devices between one of which and the work feeding device the work is gripped. 80

- during the feeding operation, means for imparting intermittent feeding movements to the devices which grip the work, and means under the control of the operator for regulating the extent of the feeding movements during the operation of the machine.
43. In a folding machine of the class described, a work feeding device, coöperating edge folding devices between one of which and the work feeding device the work is gripped during the feeding operation, means for imparting intermittent feeding movements of variable extent to the devices which grip the work, a feed controlling member arranged to occupy normally a position corresponding to a predetermined feed, and means under the control of the operator for temporarily moving the controlling member to a position corresponding to a different feed.
44. In a machine for folding pliable material, the combination with an inclined edge turning block, of feeding means comprising a supporting wheel arranged to be turned intermittently about a fixed axis always in the direction of feed, a feed finger yieldingly held toward the periphery of the wheel to engage the work and also to determine the fold line, mechanism for oscillating the feed finger while the work is engaged between it and the wheel, said mechanism being manually controlled to vary the length of the feeding steps, and means acting periodically for elevating the feed finger from the work at the conclusion of each feeding step.
45. A machine of the class described having, in combination, means for feeding a piece of material intermittently into position to have its margin operated upon, means for progressively slitting and folding the margin, and means under the control of the operator for varying the extent of the intermittent feed movements during the operation of the machine, said means comprising

ing a movable feed controlling member and 45 yielding means tending normally to move said member to one limit of its path.

46. In a machine for folding pliable material the combination with work feeding means of a slitting knife, means positively 50 connected at all times with the knife for continuously vibrating it, the path of the knife normally intersecting the material, and means under control of the operator for changing the location of the path of the 55 slitting knife to render said knife inoperative without interrupting its vibration.

47. A machine of the class described having, in combination, a frame, folding instrumentalities, a vibrating slitting knife, an 60 actuating shaft, driving connections between the shaft and knife for vibrating the knife, a spring tending to hold the knife in operative position to cut the stock, a stop for determining the limit of forward movement of 65 said knife while in operative position, and treadle operated means carried by the frame of the machine for adjusting said driving connections to render the knife inoperative.

48. A machine of the class described having, in combination, folding instrumentalities, a vibrating slitting knife arranged to operate on the work to be folded, an actuating eccentric for the knife, movable driving mechanism between the eccentric and the 75 knife, and normally stationary treadle controlled means connected at all times to the driving mechanism, whereby said connecting mechanism may be moved to shift the path of the knife without interrupting its vibration. 80

In testimony whereof, I have signed my name to this specification, in the presence of two subscribing witnesses.

CHARLES P. STANBON.
